UNITED STATES PATENT OFFICE.

WILLIAM S. HUNKINS, OF HOLLYWOOD, CALIFORNIA.

PIN TUBE.

Application filed April 18, 1928. Serial No. 270,860.

This invention relates to certain new and useful improvements in a tab end "pin tube", so called, the function of which is to properly support the pin portion of a safety pin or the like in such a manner that it will not buckle when under strain in use.

The object of the invention is to provide an exceedingly simple, easily manufactured, cheap, yet efficient tab end pin tube structure.

10 In the accompanying drawings—

Fig. 1 is a front view of the complete tab end as in use with a safety pin;

Fig. 2 is an end elevation of the pin tube itself and its supporting tab;

15 Fig. 3 is a plan view of the blank from which the pin tube is formed;

Fig. 4 is an end view of a modification.

1 Fig. 1 represents a tab of fabric. The "pin tube", so called, in its completed form provides the tube portion 1 and the slotted tab receiving and gripping portions 2—3.

Referring to the blank shown in Fig. 3, 4—5 represent slots adjacent the opposite edges thereof through which the two ends of the tab 1 may be slipped, after which the blank may be rolled up so as to form a tube 6, as illustrated in Figs. 2 and 4, those portions of the blank outside of the slots constituting gripping portions or bars which pinch down upon and hold together the two ends of the tab. The intermediate portion of the tab will be seen to surround and substantially cover the outside of the pin tube portion. By this construction, pin tubes with tab ends attached thereto ready to be sewed on to garments may be very rapidly and economically produced.

Referring to Fig. 4, it will be noted that the blank is shown as folded up so that the two tab gripping portions or bars outside of the slots do not face each other as in Fig. 2, but are located one above the other, this view being shown merely to illustrate the fact that

the particular line on which the blank is rolled up to form the tube passage is not necessarily midway between the slots.

In use, when such a tube is secured to a garment by means of the tab or otherwise, as shown in Fig. 1, it furnishes a supporting means through which the pin portion 7 of a safety pin may be easily passed, so that when it is located therein it will be held against buckling when strain is applied to the safety pin.

It will be noted that in forming the slots 4—5 the metal blank is preferably slotted as shown in Fig. 3, in such a manner as to form lips 9—10 which serve to complete the tube when it is rolled up as shown in Figs. 2 and 4.

What I claim is:

1. A pin tube formed of a strip of metal having two spaced slots adjacent the opposite edges, those parts of the strip outside of said slots forming two gripping portions, the intermediate portion of said strip between said slots forming a tubular pin passage.

2. In a device of the character described, a sheet metal strip having two slots therein adjacent the opposite edges thereof, the intermediate portion of said strip between said slots forming a pin tube, a strip of fabric extending around the outside of said tube portion, the two ends of said fabric strip passing through said slots, and being located between the two edges of the metal strip outside of the slots and held thereby.

3. A pin tube formed of a folded metal strip having therein two substantially parallel slots, and a pin passage in the fold of the strip between the said slots.

4. A pin tube formed of a folded metal strip having therein two substantially parallel slots, a pin passage in the fold of the strip between the said slots, and bendable lips adjacent to said slots.

WILLIAM S. HUNKINS.
